L. SIMMONS

NAILING BLOCK

Filed Oct. 5, 1922

UNITED STATES PATENT OFFICE.

LEO SIMMONS, OF WASHINGTON, DISTRICT OF COLUMBIA.

NAILING BLOCK.

Application filed October 5, 1922. Serial No. 592,510.

To all whom it may concern:

Be it known that I, LEO SIMMONS, a citizen of the United States of America, and a resident of Washington, District of Columbia, have invented certain new and useful Improvements in and Relating to Nailing Blocks, of which the following is a specification.

This invention relates to certain improvements

10 in nailing blocks; and the objects and nature of the invention will be readily understood by those skilled in the art in the light of the following explanations of the accompanying drawings illustrating what I 15 now believe to be the preferred mechanical expression or embodiment of my invention from among other forms, constructions and arrangements within the spirit and scope thereof.

20 In building construction, difficulties are now encountered because of the improper and insufficient anchoring of nailing blocks in the walls during the construction of the building. It is a common practice to merely insert wood blocks in the walls as the 25 bricks or tiles are laid but as the mortar does not adhere to such blocks, they thereafter become loosened and move outwardly from their sockets when base or facing boards or 30 moldings are nailed thereto or when attempt is made to refit such boards or moldings. These blocks as commonly laid in the walls ordinarily become loosened and consequently permit the boards or moldings nailed 35 thereto to move away from the surfaces of the walls, pulling the blocks outwardly from their sockets.

Also during building construction, it is 40 exceedingly difficult to locate such nailing blocks, after plaster has been applied to the walls and the blocks are thereby covered. By the methods commonly followed, much time is wasted by mechanics in endeavoring to locate such blocks because they are covered by the plaster.

45 It is an object of my invention to provide an exceedingly simple and economical nailing block, as an article of manufacture, that embodies improved anchoring means by 50 which the block is held fast and securely to its place in the wall and to prevent any outward movement or undue looseness notwithstanding shrinkage that may take place.

55 A further object of the invention is to provide a nailing block with an indicator or locating means that will be visible and prefer-

ably accessible at the exterior of the layer of plaster that covers the block.

With these and other objects in view my invention consists in certain novel features 60 of construction, and in combination and arrangements as more fully and particularly set forth and specified hereinafter.

Referring to the accompanying drawings forming a part hereof:

65 Fig. 1 is a perspective view showing part of a brick wall having nailing blocks of my invention anchored therein, one of said blocks constituting a jamb block for window or door frame parts and moldings, and the 70 other a base board block, the brick wall being partially broken away to show the base block.

Fig. 2 is a horizontal sectional view 75 through a plastered wall showing a nailing block of my invention anchored therein to form a base board block, the base board being partially broken away.

Fig. 3 is a tile partition in horizontal section showing a nailing block of my invention anchored therein to form a through block 80 to which base boards, at both faces of the partition, can be nailed.

Fig. 4 is a detail perspective view of one 85 end portion of the base board nailing block.

Fig. 5 is a detail perspective view of an 90 end portion of the jamb block of Fig. 1.

In the drawings, I show a brick wall 1, having a plaster face 2, a base board 3, fitted to said wall against the plaster face 2 95 and over the floor in the ordinary or any other suitable manner. The base board 3 is secured by nails or other fastenings driven or forced therethrough into the wood nailing blocks 6 built into the wall during the construction thereof.

Each wood nailing block 6 is usually rectangular in shape, although I do not wish to so limit my invention, and can be of any suitable and desirable dimensions, and cut 100 from any suitable lumber. However, I prefer to cut these blocks from any kind of cheap or waste lumber. According to my invention, a metal cap, preferably composed of sheet metal, is anchored to an end of 105 the block to provide the block with anchoring shoulders, flanges or projections 7 projecting laterally from the block end.

As the wall is being built up, the blocks 6 are set on a course of bricks to bring the 110 blocks at the desired elevation above the floor so that when the next course of bricks

is laid, the blocks will be anchored and included therein with bricks fitting the longitudinal faces of each block and located in front of the anchoring flanges, i. e., between said flanges and the outer vertical face of the wall. In other words, the bricks are so laid against and surrounding the blocks, that the flanges are engaged behind bricks and the blocks are thereby anchored and locked in the wall against longitudinal play or loosening even though the blocks should shrink and warp or split.

The cap that provides the metal anchoring flanges, is also anchored to the block to prevent loosening or separation of the block and anchor, even should the block shrink, warp or split.

In the example illustrated, a pair of opposite slide ways or grooves 8 are formed throughout the length of the block in its opposite sides and at their ends opening through the end faces. These grooves, in depth or transversely, converge toward the adjacent end face of the block, i. e., the grooves are inclined inwardly and toward the end face of the block that is to be covered by the cap. The grooves are preferably formed by saw cuts or kerfs and can be formed throughout the length of a piece of lumber that is to be cut up to form the blocks 6, by a pair of angularly arranged rotary saws.

These opposite converging grooves 8 form sockets in which the ends of the metal cap can be anchored. In the example shown, this cap is composed of a strip of sheet metal of the proper strength, struck up to form the intermediate flat straight body or plate 7^a, covering the end face of the block and projecting laterally therefrom. The ends of the sheet metal are then doubled back onto the front face of the projecting ends of the plate 7^a to form the strong stiff anchoring flanges 7.

The opposite end portions 7^b are then extended forwardly in approximate parallelism, from the bases of the flanges 7, to fit the opposite longitudinal side faces of the block intervening between the sockets 8 and the adjacent end face of the block.

The extremities of the sheet metal strip, extend inwardly and rearwardly to form the inclined rearwardly converging cap anchoring ends or flanges 7^c, fitting and anchored in the grooves 8, and thereby not only bracing the flanges 7, but also firmly securing and anchoring the cap to the block.

The cap can be slipped laterally onto the block, inserting the flanges 8 endwise into the ends of the grooves 8 and forcing the block laterally into the cap with said flanges sliding longitudinally in said grooves.

In fact, in manufacturing the blocks in quantities for the market, it is proposed, to cut the grooves 8 throughout the length of

a piece of lumber, and form a sheet metal cap equal in length to the piece of lumber and apply the same to the lumber, and then cut the piece of lumber and the cap thereon, to form a series of capped blocks.

The nailing block of my invention, can also be utilized as a jamb block, see 6^a, Figs. 1 and 5, to be anchored in a wall at a window or door opening, with a side and an end face exposed to receive nails securing window or door frame parts and trim or molding. Where thus used, the blocks will be anchored, as hereinbefore described, by the lateral flanges 7 of the metal cap, against movement in one direction. To anchor the block against movement in a direction longitudinally of the flanges 7, the metal cap can be formed at one end with a lateral anchoring lip or flange 7.

Where base boards are to be secured to both side faces of a partition, such as tile partition 1^a, Fig. 3, so-called "through" blocks can be employed, extending completely through the partition to receive base board securing nails in both ends.

Such through blocks can be constructed in accordance with my invention, see 6^b, Fig. 3, by placing the metal caps hereinbefore described on both ends of the block to provide said block 6^a with the anchoring flanges 7 at both ends. The flanges 7 will overlie the outer side faces of the partition 1^a, and hence one set of flanges will hold the block against longitudinal movement in one direction, and the other set of flanges against movement in the opposite direction.

Both ends of the through blocks 6^b are preferably provided with the hereinafter described locating indicators 9, and the nails securing the base boards will be driven into the blocks 6^b through the thin sheet metal caps.

Under present building methods, difficulties are encountered and time is wasted in locating the nailing blocks after walls have been plastered, preparatory to placing and securing base boards. To avoid these difficulties, I have provided the blocks with means that will be visible at the exterior of the plaster and thereby at once locate the positions of such blocks. For instance, in the example shown, I show a comparatively long free end length of string, twine, wire, or the like 9, at one end secured to the outer or front end of the block 6, by a nail, staple, brad, or the like 10, driven into the block end. The blocks are provided with these indicators before being placed on the market, or used. When the plaster 2 is applied to the wall and over the front or outer ends of the blocks 6, the indicator or locating lengths 9 can be held or manipulated, if that be necessary, so as to extend to and be visible at the exterior of the plaster, and thus clearly indicate the location of the

hidden blocks 6, to the mechanics when fitting the base boards and nailing the same to the blocks.

It is evident that various changes, modifications, and variations might be resorted to without departing from the spirit and scope of my invention, and hence I do not wish to limit myself to the exact disclosures hereof.

10. What I claim is:

1. A nailing block provided with a metal cap providing oppositely projecting lateral block anchoring flanges and having an anchoring extension arranged at corresponding ends of and transversely with respect to the flanges and projecting laterally therefrom approximately parallel with a side face of the block.

2. A nailing block provided with anchoring flanges arranged transversely and longitudinally with respect to the blocks to hold the block against movement longitudinally of the wall and also against movement transversely of the wall, whereby said block can be employed as a jamb block.

3. A nailing block having transverse

grooves across opposite sides, in combination with a metal end cap formed to fit the inner end of the block and to project laterally beyond side faces of the block to anchor the block in a wall against outward movement, said cap formed to slide onto the block transversely thereof and having projecting tongues to enter said grooves and interlock the cap with the block and thereby prevent outward movement of the block with respect to the cap.

4. Means for anchoring a nailing block in a wall against outward movement, consisting of a metal cap formed with a pair of opposite projecting block anchoring ends, and having opposite side flanges to fit opposite side faces of the block, said flanges formed with inturned converging tongues constructed and arranged to anchor in grooves in opposite sides of the block to thereby lock the block to the cap against outward movement of the block with respect to the cap.

Signed at Washington, D. C. this 4th day of October 1922.

LEO SIMMONS.
